UNITED STATES PATENT OFFICE.

MAURICE C. PIERCE, OF MADISON, WISCONSIN.

COMBINATION TELEPHONE ATTACHMENT.

1,251,098.

Specification of Letters Patent. Patented Dec. 25, 1917.

Application filed March 12, 1917. Serial No. 154,200.

To all whom it may concern:

Be it known that I, MAURICE C. PIERCE, a citizen of the United States, residing at Madison, in the county of Dane and State 5 of Wisconsin, have invented certain new and useful Improvements in Combination Telephone Attachments, of which the following is a specification.

My invention relates to devices possessing 10 artistic, utilitarian and advertising value and the objects of my invention are first; to to provide a neat and attractive device; second, to provide a satisfactory and convenient means of displaying advertising; third, 15 to combine advertising value with convenience to the user in such manner that the advertising purposes will be obscured by the usefulness of the device; fourth, to combine in one device an emergency directory 20 of important calls, a classified directory containing but one name in each profession or business, a fixed or renewable calendar, a fixed or renewable memorandum pad, a pencil and a means for listing the telephone numbers of 25 personal friends, etc., a sounding board and a guard for the transmitter, the entire device designed to display in plain sight and in convenient manner all of the requisites to facilitate the useful employment of a telephone in emergency or business; fifth to provide 30 a device light in weight and without the use of unnecessary metal parts thus minimizing cost and weight.

The above and other objects which will be 35 apparent upon perusal of the following specification are attained by the combination and arrangement of parts fully illustrated in the accompanying drawings in which—

Figure 1, is a front elevation of my complete device attached to a desk telephone.

Fig. 2, is a side elevation of the complete device attached to a desk telephone.

Fig. 3, is a horizontal section taken on line A—A Fig. 1.

Fig. 4, is a plan of the memorandum pad.

Fig. 5, is a side elevation.

My invention comprises a plate 1 ornamental in shape and provided with a central annular aperture 7 through which the 30 threaded neck of a telephone transmitter passes, said plate 1, being in close engagement with the diaphragm case 9, by the shoulder 10 of the transmitter 11. Cut out portions are provided on each side of said 35 plate 1 approximate the lower terminus

thereof to allow the removal of the transmitter from its retaining hook without coming in contact with said plate and causing damage thereto.

Near the top of said plate is placed in any 60 desired manner a directory of important phone numbers comprising preferably the telephone numbers of the police and fire stations and the number of the telephone to which the said device is attached. Any desired numbers can be substituted without departing from the spirit of my invention although said top space is designed to be used for emergency calls.

On either side of the transmitter are arranged 70 two panels 12, bearing a list of professional men or merchants preferably alphabetically arranged according to profession or trade for easy and convenient reference.

A distance above the transmitter 11, and equi-spaced from the longitudinal center of said plate 1, are disposed two vertical slots 13. A strip of material 15, preferably cloth of a stiff and close woven nature is passed 80 through said slots and the ends 16 fastened in any desired manner to the back of said plate as plainly illustrated in Fig. 3. A calendar pad 14 of any preferred design is provided with a support 17 tapering toward its 85 lower edge and said support adapted to be retained in close relation to the plate 1 by the loops 15. A distance below said transmitter and equi-distant from the longitudinal center of the plate 1 are disposed two 90 vertical apertures 19. Through said apertures 19 a strip of any suitable material is inserted forming a loop 2. The ends 18 thereof are secured to the back of said plate in any preferred manner. A pad 20 is provided with a support 3 similar to that provided for the calendar aforementioned, said support being held in close relation to plate 1 by means of the loop 2. Said pad is preferably divided into two unequal sections 100 longitudinally thereof by perforations 4 and the upper section designed to bear advertising matter and the bottom section to be used for noting messages, phone numbers and so forth.

A loop 21 formed of a single strip of material preferably cloth of wear resisting nature is fastened in such manner that it extends upward a distance beyond the scratch pad 20. A pencil 22 is inserted in 105

said loop and rests on top of said pad 20. Said pencil is designed to bear advertising matter.

In the upper right hand corner of the plate 1 is placed a fastener 23 passing through said plate and securing one or more cards 25 provided with tabs or index portions 24. The cards being preferably ruled transversely in order that writing appearing on them will be convenient for reading. Said cards so fastened that their lower edges will rest on the threaded neck of the transmitter and their upper edges flush with the top of the plate 1 excepting the tab 24 which extends upward a distance beyond the upper edge of said plate. It is obvious that any number of cards may be arranged in this manner and indexed either alphabetically, numerically, chronologically or in any preferred manner. In the present instance however the cards are designed as a means for having for instant and convenient use the telephone numbers of personal friends or business acquaintances frequently used.

Claims—

1. A device of the class described embodying a base plate having a central opening therein adapted to fit over a telephone transmitter, said base plate also having its lower corners cut away to facilitate the removal of the telephone receiver, advertising panels or spaces upon said base plate and a scratch pad secured to the plate.
2. A device of the class described embodying a base plate having a central opening therein adapted to fit over a telephone transmitter, said base plate also having its lower corners cut away to facilitate the removal of the telephone receiver, the material between said cut away corners defin-

ing a depending elbow, advertising panels or spaces upon said base plate and a scratch pad secured to the depending elbow.

3. A device of the class described embodying a base plate having a central opening therein adapted to fit over a telephone transmitter, said base plate also having its lower corners cut away to facilitate the removal of the transmitter, advertising panels or spaces upon said base plate, and memoranda slips pivotally secured to the back of the base plate at the upper corner thereof.

4. A device of the class described embodying a base plate having a central opening therein adapted to fit over a telephone transmitter, said base plate also having its lower corners cut away to facilitate the removal of the telephone transmitter, advertising panels or spaces upon said base plate, a scratch pad secured to the base plate below the opening and a calendar secured to said base plate above the opening.

5. A device of the class described embodying a base plate having a central opening therein adapted to fit over the transmitter of a telephone, said plate also having its lower corners cut away to facilitate the removal of the telephone receiver, advertising panels or spaces upon either side of said opening, a calendar secured to the base plate above the opening and between the advertising spaces, a scratch pad secured to the base plate below the opening and a pencil secured to the base plate.

In testimony whereof I affix my signature in the presence of two subscribing witnesses.

MAURICE C. PIERCE.
